UNITED STATES PATENT OFFICE

MARTHA GOLDMAN, OF NEW YORK, N. Y.

DESIGN FOR A NOVELTY JEWELRY PENDANT

Application filed February 10, 1933. Serial No. 47,174. Term of patent 3½ years.

To all whom it may concern:

Be it known that I, MARTHA GOLDMAN, a citizen of the United States, residing at 140 West 69th St., in the county of New York, State of New York, have invented a new, original, and ornamental Design for a Novelty Jewelry Pendant, of which the following is a specification, reference being had to the accompanying drawing, forming part thereof.

The figure shows a front perspective view of the novelty jewelry pendant of my design. The drawing is shaded to show contrasting colors. The substantially circular elements illustrated in the drawing are spherical in shape, while the elements representing arms and legs are rectangular in cross-section.

I claim:

The ornamental design for a novelty jewelry pendant, as shown, and described.

MARTHA GOLDMAN.
